UNITED STATES PATENT OFFICE.

EDWARD J. KING AND THOMAS R. KENNEDY, OF ROCHESTER, NEW YORK,
ASSIGNORS TO THE CO-OPERATIVE FOUNDRY COMPANY, OF SAME
PLACE.

DESIGN FOR A HEATING-STOVE.

SPECIFICATION forming part of Design No. 33,311, dated October 2, 1900.

Application filed September 10, 1900. Serial No. 29,606. Term of patent 7 years.

To all whom it may concern.

Be it known that we, EDWARD J. KING and THOMAS R. KENNEDY, citizens of the United States, residing in the city of Rochester, county of Monroe, and State of New York, have invented and produced a new and original Design for a Heating-Stove; and we do hereby declare the following to be a full, clear, and exact description of the same, in connection with the accompanying drawing, forming a part thereof.

Our design consists of the shape and configuration of the stove shown and the ornamentation applied thereto.

In the drawing we have shown a perspective view of a heating-stove embodying our design, in which—

The lower base-section (indicated by A) is supported upon the legs a, the upper portions of which are provided with the ornamentation shown, and between the legs the base A is provided with the scroll and leaf ornamentation b. The upper base-section B rounds inwardly toward the top, and at its corners is the conventional ornamentation C. Upon the front side of the base-section is the ash-pit door D, having the Maltese cross d in its center, upon either side of which are the scroll and leaf ornaments d'.

Rising above the base-section B is the fire-pot E, and supported by the latter is the circular stove-body F, around the lower end of

which is a depending annular flange G, provided with scroll ornamentation, as shown, and having upon its sides curved rails g. 35

H indicates the lower front door, having the ornamented damper h arranged at its center and provided upon its sides and bottom and at its upper corner with the scrolls and leaves j.

I indicates the upper front door, having the mica-openings and ornamented about its edges with leaves and scrolls k. Ornamental rounded panels M, having the scrollworks m, are arranged upon opposite sides of the front 40 doors H and I, as shown.

Surmounting the body F is the top section N, having the plain band n, provided at the sides and front with the ornamental portions n', and above this are the ornamental zones 50 O and P. At the extreme top of the stove is the urn-like ornament Q.

The ornamentation of the stove as a whole is consistent, and the various parts harmonizing produce a pleasing effect. 55

We claim—

The design for a heating-stove substantially as herein shown and described.

EDWARD J. KING.
THOMAS R. KENNEDY.
